His Attorney.

UNITED STATES PATENT OFFICE.

JAMES R. CRAIGHEAD, OF SCHENECTADY, NEW YORK, ASSIGNOR TO GENERAL ELECTRIC COMPANY, A CORPORATION OF NEW YORK.

REGULATING SYSTEM.

Application filed August 2, 1926. Serial No. 126,382.

My invention relates to regulating systems and more particularly to voltage regulating systems for alternating current circuits.

In alternating current systems of distribution it is desirable for many purposes to separate the load on a transformer supplied from a primary supply circuit of constant potential into two branches; the one branch being a heavy load having considerable effect on the regulation of the transformer, and the other branch being a comparatively small load whose effect on the regulation of the transformer is small. It is evident that if both loads are connected in multiple to the transformer secondary, changes in the heavy load, as for instance, elevator motors will cause changes in the voltage applied to the small load comprising translating devices which, for instance, may be incandescent lamps. Since incandescent lamps are sensitive to voltage variations, objectionable lamp flicker will occur. The foregoing illustration of elevator motors and incandescent lamps is paralleled in potential transformer practice by a heavy load consisting of a synchronism indicator and a light load comprising translating devices such as a voltmeter and wattmeter. In either case, it is equally desirable that the regulation of the transformer shall not cause the voltage on the load of constant-voltage characteristics to vary.

An object of my invention is to prevent objectionable variations in the voltage impressed on load circuits which require substantially constant voltage when said load circuits are energized in parallel from the same transformer with load circuits having electrical characteristics which cause variations in the ratio of voltage transformation and phase angle of said transformer.

My invention will be better understood from the following description taken in connection with the accompanying drawing, and its scope will be pointed out in the appended claims.

In the drawing, Fig. 1 is a diagrammatic illustration of an embodiment of my invention, particularly adapted for metering applications; Fig. 2 is a modification thereof adapted for general applications; and Fig. 3 is a further modification of the arrangement shown in Fig. 2.

Referring to Fig. 1 of the drawing, 1 indi-

cates the conductors of an alternating current supply circuit. A potential transformer 2 having a primary winding 3 and a secondary winding 4 is connected to be energized from the supply circuit. A light load device, such as a voltmeter 5, and a comparatively heavy load device, such as a synchronism indicator 6, are connected in parallel across the secondary winding 4 of the main transformer. An auxiliary transformer 7 having a primary winding 8 and a secondary winding 9 is connected to be responsive to the voltage of the supply circuit 1. The voltmeter 5 is provided with a main actuating winding 10 and an auxiliary actuating winding 11. The main actuating winding 10 is connected to be responsive to the voltage across the secondary winding 4 of the main transformer. The secondary winding 9 of the auxiliary transformer is connected to the secondary winding 4 of the main transformer and through the auxiliary winding 11 of the voltmeter to the other side of the secondary of the main transformer.

The secondary windings 4 and 9 are connected and arranged so that when the secondary winding of the main transformer develops the same voltage, with due regard to the ratio of turns, as is supplied to the primary winding, the resultant voltage of windings 4 and 9 will be zero. When, due to the effect of the heavy load 6, the secondary winding 4 of the main transformer develops less voltage, with due regard to the ratio of turns, than is supplied to the primary winding 3, the difference of voltage is applied to the auxiliary coil 11 in such a manner that the total effect of the two coils in the voltmeter will give practically a constant reading in spite of changes in the heavy load on the main transformer. The electromotive force produced in the winding 11 is equal to the difference between the supply circuit voltage and the load circuit voltage when the supply circuit voltage is divided by the transformer turn ratio.

Referring to Fig. 2, a somewhat similar arrangement is shown, but in this case the difference of the voltage generated by the main transformer 2 and the auxiliary transformer 7 is applied through a second auxiliary transformer 12, having a primary winding 13 and a secondary winding 14. A load circuit 15 of constant voltage characteristics, shown diagrammatically as incandescent lamps, is con-

nected in parallel across the secondary of the main transformer with a frequently variable heavy load circuit shown as a motor load 16. The primary winding 13 of the second auxiliary transformer is connected to be responsive to the difference in voltage between the main transformer 2 and the auxiliary transformer 7. The secondary winding 14 of the auxiliary transformer 12 is connected in series with the load circuit 15. In this case the difference in voltage generated by transformers 2 and 7 is applied to the primary winding 13 of transformer 12 which furnishes a voltage through its secondary winding 14 in series with the voltage of the main transformer 2 to maintain a substantially constant voltage across the incandescent lamp circuit with changes of load on the motor circuit.

In Fig. 3, the main transformer 2 is shown connected in the same manner as in Fig. 2, but the auxiliary transforming means comprises a transformer 17 having a three-legged core 18. A primary winding 19 is positioned on one leg, a secondary winding 20 is positioned on another leg, and a tertiary winding 21, usually arranged with the same number of turns as the secondary winding 20, is positioned on the middle leg. The primary winding 19 is connected to be energized from the supply circuit 1. The secondary winding 20 is connected in parallel with the secondary winding 4 of the main transformer, and the tertiary winding 21 is connected in series with the load circuit 15. A variable load circuit, shown as a motor load 16, is connected in parallel with the load circuit 15 across the secondary of the main transformer 2.

The operation of the arrangement shown in Fig. 3 is as follows: If it be assumed that the motor load 16 represents an elevator motor load or similar motor load, starting and acceleration of the motor will require heavy fluctuating currents which would ordinarily cause poor regulation on the main transformer with consequent variations in voltage impressed across the lamp circuit. The secondary windings 4 and 20 of the transformers 2 and 17 respectively are so positioned and arranged that for light load conditions, the two secondary windings develop voltages which are equal and in opposition. When, due to the effect of the motor load, the secondary winding 4 of the main transformer develops less voltage, with due regard to the ratio of turns, than is supplied to its primary winding, the auxiliary transformer receives different voltages on its primary and secondary windings. If these voltages were equal, the flux developed in the core 18 would pass only through the primary winding 19 and the secondary winding 20 and no voltage would be generated in the tertiary winding. However, since these two voltages are unequal, the flux developed on the primary side of the core 18 will be greater than that developed on the secondary side and the

difference in flux will pass through the tertiary coil 21 and generate a voltage proportional to the difference of voltage between the primary winding 19 and the secondary winding 20. This voltage is introduced in series with the load circuit 15 and will maintain a substantially constant voltage across the lamp circuit with variations in voltage across the secondary of the main transformer. It will be apparent, however, that the tertiary winding 21 may be arranged to excite an auxiliary coil in an instrument, similarly to the arrangement shown in Fig. 1, instead of introducing a corrective voltage in series with the load of constant voltage characteristics. Whether an auxiliary coil in an instrument is energized by a corrective voltage and a main coil is energized by the voltage from the main transformer, or the resultant voltage applied directly to translating devices such as instruments or lamps is obtained by introducing a corrective voltage in series with the voltage from the main transformer, there is in each case a composite energization or effect.

The auxiliary transformers as shown in each of the figures may be very much smaller units than the main transformer. It is also to be noted that, since the whole scheme of correction is based on the difference between the primary and secondary voltages of the main transformer, with due regard to the ratio of turns, the correction will obviously apply to phase angle between primary and secondary voltage as well as to ratio. This feature is important for all applications in metering.

While I have shown and described several embodiments of my invention, it will be obvious to those skilled in the art that changes and modifications may be made without departing from my invention, and I, therefore, aim in the appended claims to cover all such changes and modifications as fall within the true spirit and scope of my invention.

What I claim as new and desire to secure by Letters Patent of the United States, is:—

1. In combination, an alternating current supply circuit, a transformer connected to said supply circuit, a load circuit comprising a plurality of branch circuits connected in parallel to be energized from said transformer, and means for introducing into one of said branch circuits an electromotive force proportional to the difference between the supply circuit voltage, divided by the transformer turn ratio, and the load circuit voltage.

2. In combination, an alternating current supply circuit, a main transformer connected to said supply circuit, a load circuit comprising a plurality of branch circuits connected to be energized in parallel from said transformer, a winding associated with one of said branch circuits, and an auxiliary transformer for interconnecting said supply circuit and

5 said winding for applying to said winding a voltage dependent upon the difference between the voltage applied to said auxiliary transformer and the voltage of said load circuit.

6 3. In combination, an alternating current supply circuit, a main transformer connected to said supply circuit, a plurality of load circuits arranged to be energized in parallel 10 from said transformer, an auxiliary transformer having its primary winding connected to said supply circuit, a winding connected to have a voltage produced therein dependent upon the difference between the voltage 15 of the secondary winding of said auxiliary transformer and the voltage of one of said load circuits, and means for combining the energization from said winding and the voltage of said one of said load circuits to produce 20 the effect of a voltage in another of said load circuits which is substantially unaffected by the variations in ratio of voltage transformation and phase angle of said main transformer upon changes of load in said 25 first-mentioned load circuit.

4. In combination, an alternating current supply circuit, a main transformer connected to said supply circuit, a plurality of load circuits arranged to be energized in parallel 30 from said transformer, and means for introducing a voltage in series with one of said circuits comprising a winding connected to be energized in accordance with changes in the ratio of transformation of said main 35 transformer due to changes in load in the other load circuit.

5. In combination, an alternating current supply circuit, a main transformer connected to said supply circuit, a plurality of load 40 circuits connected to be energized in parallel from said main transformer, an auxiliary transformer having a primary winding connected to said supply circuit and a secondary winding connected to the secondary winding of said main transformer, and a third winding associated with the windings of said auxiliary transformer for supplying a corrective voltage to one of said load circuits in accordance with the variations in the ratio of 45 voltage transformation of said main transformer from its theoretical value.

6. In combination, an alternating current supply circuit, a main transformer connected to said supply circuit, a load circuit of constant voltage characteristics, and a load circuit of variable current characteristics connected to be energized in parallel from said main transformer, an auxiliary transformer having a primary winding connected to said supply circuit and a secondary winding connected to the secondary winding of said main transformer, and a third winding associated with the windings of said auxiliary transformer for maintaining a voltage in said first 55 mentioned circuit substantially unaffected by

the variations in the ratio of voltage transformation and phase angle of said main transformer from its theoretical value.

7. In combination, an alternating current supply circuit, a main transformer connected 70 to said supply circuit, a circuit from which a load requiring a substantially constant voltage is energized, a circuit from which a load requiring comparatively larger and variable amounts of power is energized, said load circuit 75 being arranged to be connected in parallel with said main transformer, and an auxiliary transformer comprising a primary winding connected to said supply circuit, a secondary winding connected to be responsive 80 to the secondary voltage of said main transformer, and a tertiary winding connected and arranged for introducing a voltage in series relation with said first mentioned circuit in accordance with the variations in the ratio 85 of voltage transformation of said main transformer from a predetermined value.

8. In combination, an alternating current supply circuit, a main transformer connected to said supply circuit, a circuit from which 90 a load requiring a substantially constant voltage is energized, a circuit from which a load requiring varying amounts of power is energized, said load circuits being arranged to be energized in parallel from said main 95 transformer, an auxiliary transformer connected to said supply circuit and arranged for generating a secondary voltage equal to the open circuit secondary voltage of said main transformer, and a winding in circuit with 100 said first mentioned load circuit connected to be responsive to the difference in voltage between the secondary windings of said main and auxiliary transformers.

9. In combination an alternating current supply circuit, a main transformer connected to said supply circuit, a circuit from which translating devices are energized, a circuit from which a load requiring varying amounts of power is energized, said circuits being connected to be energized in parallel from said main transformer, an auxiliary transformer having a core comprising three winding legs, a primary winding on one of said legs connected to said supply circuit, a secondary winding on 105 another of said legs connected to the secondary winding of said main transformer, and means comprising a tertiary winding on the remaining leg arranged to produce a corrective voltage for supplying in conjunction with said main transformer a composite energization to the translating devices of said first-mentioned circuit substantially unaffected by variations in the secondary voltage of said main transformer.

10. In combination an alternating current supply circuit, a main transformer connected to said supply circuit, a circuit from which a load requiring a substantially constant voltage is energized, a circuit from which a load

requiring varying amounts of power is energized, said load circuits being arranged to be energized in parallel from said main transformer, an auxiliary transformer having a core comprising two outside legs and an intermediate leg, a primary winding on one of said outside legs connected to said supply circuit, a secondary winding on the other of

said outside legs connected to the secondary winding of said main transformer, and a tertiary winding on said intermediate leg for supplying a corrective voltage to said first mentioned circuit.

In witness whereof, I have hereunto set my hand this 30th day of July 1926.

JAMES R. CRAIGHEAD.
